UNITED STATES PATENT OFFICE.

THEODORE TEBOW, OF NICHOLASVILLE, KENTUCKY.

MACHINE FOR DRESSING HEMP, FLAX, AND OTHER FIBROUS SUBSTANCES.

SPECIFICATION forming part of Letters Patent No. 290,494, dated December 18, 1883.

Application filed March 12, 1883. (No model.)

To all whom it may concern:

Be it known that I, THEODORE TEBOW, a citizen of the United States, and a resident of Nicholasville, in the county of Jessamine and State of Kentucky, have invented certain new and useful Improvements in Machines for Dressing Hemp, Flax, and other Fibrous Substances, of which the following is a specification.

My invention relates to improvements in machines for hackling or dressing hemp, flax, and other similar fibrous matter, and has for its objects to provide novel means for causing the hackle-teeth to continuously advance into and recede from the suspended hemp; to provide novel means for stripping the hackle-teeth of adhering tow or other matter, and to provide a novel device to feed the hemp gradually into position for dressing, and at the same time move it laterally for causing the hackle-teeth to pass through different fibers alternately.

The invention has other objects, all of which will be hereinafter set forth.

The objects of my invention I accomplish by the mechanism hereinafter described and claimed, and illustrated in the accompanying drawings, in which—

Figure 1 is a longitudinal elevation of a hemp-hackling machine embodying my invention. Fig. 2 is a similar view of the opposite side of the machine. Fig. 3 is a sectional plan on line $x-x$, Fig. 2. Fig. 4 is a detail transverse sectional view on line $x-x$, Fig. 5, of the zigzag-grooved sliding box for vibrating the feeding-clamps. Fig. 5 is a detail plan view of the same device shown in Fig. 4. Fig. 6 is a detail end elevation of the clutch-collar on the hackle-wheel shaft. Fig. 7 is a detail elevation of the clutch and pulley device on the hackle-wheel shaft for stopping and starting the mechanism for operating the feeding-frame toward and from the hackle-wheel. Fig. 8 is a transverse section of the feed-clamp, and Fig. 9 is a detached perspective view of the feed-clamp and its supporting uprights.

A A represent the longitudinal bars, and A' A' the legs composing the supporting-frame of the machine.

B represents a driving-shaft, suitably jour-

naled in boxes within the lateral extension A" of the frame.

B' represents a driving-pulley, and B" a transmitting-pinion, both being mounted on 55 shaft B.

C is a skeleton wheel, composed of hubs C' C' and slotted arms C" C", and mounted on a shaft, D, suitably journaled in boxes a a on the bars A A of the supporting-frame. 60

D' is a large gear-wheel keyed to shaft D, and meshing with pinion B", by which it is driven.

E E represent transverse bars armed with hackle-teeth e, and mounted at their ends on 65 slides E' E', which reciprocate in the slots or ways e' of wheel-arms C".

b b are metal straps or loops attached to the slides E', and moving upon plates b', which are secured to the front faces of the arms C". Straps 70 b, sliding upon plates b', cause the slides E' to move freely within the slots close upon their seats of motion.

d d are rollers pivoted upon the slides E'.

F F represent suitable roller-guides at both 75 sides of the machine, formed by the bars f f, secured to frame-bars A. Guides F are preferably perpendicular between their curved inlets and outlets, so that the operation of the hackle-teeth upon the hemp will be in a downward straight line, and a long thorough vertical pull or passage through it obtained. Rollers d travel in guides F to properly advance and retract the hackle-teeth in their rotary movement. The arrows in Figs. 1, 2, and 3 85 indicate the direction of movement of wheel C.

c c are angular metal straps securing and connecting the outer ends of the bars forming the slotted arms C".

G G represent transverse bars mounted on 90 slides G' at their ends, which travel in the slots or ways e' of the arms C" upon the hackle-bar slides E'.

g g are rollers pivoted upon the inner ends 95 of slides G', and traveling a portion of their rotary movement in a cam-guide, g', to advance the bars G over the hackle-teeth e, as they leave the hemp, to strip or clean them of tow or other adhering matter. Hackle-teeth e are preferably set at an angle to the bars E, 100 whereby the teeth are caused to project downward on approaching the hemp, so that they

may enter it as early as possible in their rotary movement and draw it toward them, and holding it more firmly than if arranged radially.

5 H H represent the base-bars, and H' H' the uprights or posts composing the hemp-feeding carriage-frame.

h h represent rollers, upon which the feeding-frame is mounted.

10 I I' represent two clamping-bars extending across the machine, and preferably of wood, between which the hemp is placed. The butt-ends or roots of the hemp are first placed between the clamping-bars I I' for dressing, and 15 the balance of it permitted to hang in the path of the rotating hackle-teeth, which have sufficient movement to dress the longest fibers. The butts can be easily dressed by clamping the dressed portion between the clamping-bars 20 I I'.

From this operation more long hemp and less tow would result than by any other method or by machines known to me:

i i are strengthening strips of metal in the clamping-bars I I'.

25 i' i' are strips of rubber or cushioning material, secured by and between metal strips i" i", to the clamping inner faces of clamping-bars I I', making a strong tenacious hold for the hemp.

J is a strip of muslin or other fabric covering the rubber strip on the bar I', passing beneath the strips i" to assist in holding the said rubber firmly in place.

30 J' J' are straps or yokes, pivotally secured to the ends of the bar I and made to swing upon the adjustable bar I. Bar I slides within the yokes J', to be clamped firmly upon the hemp placed between it and the bar I' by hand pressure-screws j j.

K are studs or pins at the ends of bar I, on 35 which the clamp pivots in bearings k, made in the upper ends of bars K'. Bearings k are preferably open slots, as shown, so that the clamp can be readily attached and detached. The feed-clamp is held in the inclined position shown for the proper suspension of the

40 hemp by one or more bolts, n, as in Fig. 2, which may be made to enter openings in the ends of the lower bar, I', and kept in position by the movable spring n'.

45 Bars K are pivoted intermediate of their ends to the uprights H'.

L is a roller suspended from a bracket, L', at the lower end of one of the pivotal bars K'.

l is a sliding box, mounted upon an outward extension, M, of one of the main-frame bars A.

l' is an irregular or zigzag groove made in box l, into which the roller L is suspended.

m is a pitman attached at one end to the box 50 l, and connected at its other end with the gear-wheel D'.

Box l is reciprocated by pitman m, its zigzag groove l' causing the roller L to move laterally and the pivotal bars K' to vibrate. The lateral movement of the bars K' 55 causes the clamping-bars I I', mounted thereon, to carry the hemp suspended therefrom to move in different paths of travel of the hackle-

teeth, resulting in a thorough dress of the hemp.

N is a transverse tie-board connecting the 70 uprights H' of the feeding-frame.

O O are vertical fenders attached to back board, N, to prevent the entrance of hemp suspended from the clamp-bars into the slotted arms C' of the hackle-wheel, that would 75 clog and choke them, thereby interfering with the operation of the sliding parts of the hackle-teeth and stripper-bars.

P P' represent ropes attached at their ends to the feeding-frame and connecting with a 80 winding shaft or drum, p, suitably journaled at the rear end of the machine.

Q is a belt connecting cone-pulley R or shaft p with driving cone-pulley Q' or wheel-shaft D.

S represents an ordinary clutch device for 85 bringing loose cone-pulley Q into and out of engagement with the revolving shaft D.

S' is an ordinary clutch-lever for bringing into and out of gear the clutch devices. It is provided with a cam projection or ridge, s, at 90 its free end, which comes in contact with an inclined face or cam projection, s', on one of the base-bars H of the feeding carriage or frame, to automatically shift said clutch-lever and stop the winding operation of ropes P P' 95 when the feeding-carriage has approached the desired position toward the hackle-wheel.

TT are inclined tracks, upon which the feeding-carriage moves to elevate the clamp-bars as they approach the hackle-wheel, and place them as near as possible to the hackle-teeth without coming in contact with them. These inclined tracks permit and aid materially in the ready withdrawal or backing of the feed-carriage from action, which is accomplished 100 by the attendant or operator. The back-board or tie-board N approaches close to the points of the hackle-teeth in the forward movement of the carriage, and prevents the hemp from sliding off or retreating from said teeth during their operation upon it.

U represents a platform at the rear end of the feed-carriage for the operator to stand upon in adjusting the hemp to and from the clamping devices.

115 The operation of my machine is as follows: The hemp to be dressed is first clamped by its butt-ends between the clamping-bars I I', permitting it to hang freely in front of the hackle-wheel. The hackle devices being set in motion and the clutch-lever S' shifted so as to bring the winding-shaft p into motion, the feed-carriage is then slowly drawn toward the hackle-wheel, whose teeth advance gradually into the hemp, pass through and cut its fibers, and recede therefrom at the lowermost point of travel of the outer ends of the wheel-arms C'. The advance of the feed-carriage having been retarded by the adjustment of the clutch device, and the hemp sufficiently dressed, it 120 is then returned to its normal position out of the path of the hackle-teeth, and the hand-screws of the clamping-bars I I' adjusted so that said hemp may be extracted therefrom, and 125

130

that part of the hemp previously held between said clamp-bars subjected to the same operation as above. The long, steady, and successive passage of the hackle-teeth through the 5 hemp insures a perfect dress, and a very limited amount of tow results therefrom in the operation of my machine.

I claim—

1. In a machine for dressing fibrous substances, the combination, with the revolving shaft, the radial arms having slots, the toothed bars arranged to reciprocate in the slots, and having friction-rollers at their ends, of the vertical guides F, having curved inlets and outlets, substantially as shown and described. 15

2. In a machine for dressing fibrous substances, the combination of the slotted arms, the hackle-teeth bars, the stripper-bars, and means for reciprocating the hackle-teeth bars 20 and advancing and retracting the stripper-bars over the hackle-teeth, substantially as described.

3. In a machine for dressing fibrous substances, the combination of the adjustable 25 clamping-bars I I' with a carriage carrying said bars, a winding-drum, a rope connecting

the drum with the carriage, and a clutch for operating the drum, substantially as and for the purpose described.

4. In a machine for dressing fibrous substances, the combination of a revolving wheel or cylinder, hackle-teeth carried thereby, a feed-carriage, ways on which the carriage may move, clamping-bars I I', upright pivoted bars K', a grooved box, l, and a connection between 30 the upright pivoted bars and the grooved box, substantially as and for the purpose described. 35

5. In a machine for dressing fibrous substances, the combination of hackling devices, a feed-carriage, means for advancing the carriage toward the hackling devices, clamping-bars I I', mounted on the carriage, the back board, N, and fenders O, substantially as and for the purpose described. 40

In testimony whereof I have hereunto set 45 my hand in the presence of two subscribing witnesses.

THEODORE TEBOW.
